Application September 22, 1941, Serial No. 411,775

7 Claims. (Cl. 103—38)

The present invention relates to pumps and specifically to rotary pumps having reciprocating pistons.

Among the objects of the invention is a variable delivery pump of the type indicated in which the delivery may be regulated either automatically by the pressure of the fluid delivery or manually.

Another object is a pump of the type indicated in which the delivery varying or changing means is of simple construction and may be incorporated within the pump unit.

Another object is a multicylinder pump of large capacity capable of being built into a small volume unit.

Another object is a reciprocating piston pump in which the piston stroke is variable by means of simple effective means not likely to get out of order, and which may be easily and economically produced.

Still other objects and advantages will be apparent to those skilled in the art upon reference to the following description and the accompanying drawings in which

Fig. 1 is a central vertical longitudinal section through a pump embodying the present invention.

Fig. 2 is a section on line 2—2 of Fig. 1.

Fig. 3 is a section on line 3—3 of Fig. 1.

Fig. 4 is a section on line 4—4 of Fig. 1.

Fig. 5 is a section on the line 5—5 of Fig. 1.

Figs. 6, 7, 8 and 9 are views in elevation of the several secondary cams.

Fig. 10 is an end view of the cam carrying shaft.

Figs. 11 and 12 are views showing the relative position of the secondary cams under different conditions.

As indicated in the drawings, the pump, forming an illustrative embodiment of the invention, consists of a U-shaped housing 15 provided with a suitable cover plate 16 in which are an inlet 17 and outlet 18. The housing 15 and cover 16 are each provided with a longitudinally extending bearing portion 20 which together with the pump rotor 25 serve to separate the inlet from the outlet. The two open ends of the U-shaped housing are closed by means of end members which support the pump mechanism.

The rotor 25 consists of a hollow cylinder whose walls are sufficiently thick to provide for the formation therein of a plurality of cylinders 26, there being shown six of these arranged in pairs of which the members are diametrically opposite

and in axial alignment, while the several pairs are equiangularly displaced from each other.

Arranged to reciprocate in each pair of cylinders, is a double piston 27, the connecting member of which is provided with a centrally located circular opening, within which is a rotatable member or cam 28 having a rectangular opening 29 eccentrically located therein. Suitable anti-friction bearings for member 28 are indicated at 28c.

Extending through the several openings 29 is a shaft 35 having at that portion within the several connecting members a plurality of square sections 36, one for each of the members, which shaft is supported at or near its ends in eccentric or circular cams 37, the latter being fixed to the shaft 35 by suitable keys (see Fig. 5).

The cams 37 are themselves rotatably mounted in suitable bearings 37a in other circular cams or eccentric 38 and 138, rotatably mounted in bearings 38a. The support for one of said other cams, 138, is a suitable ring 38b, carried by the rotor 25, while the support for cam 38 is a ring or flange 38c forming a part of the end cover 40.

The end cover member 40 consists of a plate fitting one end of housing 15 and provided with a circular flange 38c and with a central bore 41.

The member 40 is also provided with a diametrically arranged chamber 42 in its outer portion, and in said chamber is located a plunger 43, supported by springs 44 and 45, and provided with an opening in which, with suitable bearings 46, is rotatably arranged the end of shaft 35, this extending beyond the adjacent cam 37 and into the bore 41. Bore 41 is of sufficient size to permit considerable movement of the shaft 35 with vertical movements of plunger 43.

The other end of the housing 15 is closed by a member 50 having a central bore through which extends the drive shaft 51, this being provided with a flange 52, by means of which it may be secured to the rotor 25 as by means of screws 53.

The flange portion 52 is, on its inner face, provided with a smooth surface 54 against which abuts this end of the shaft 35, a suitable thrust ball 55 or other bearing element being used.

At its other end, shaft 35 is provided with a thrust bearing such as the ball 56 and a thrust plate 57 therefor. The latter is preferably a screw plug serving also to close the central bore in the end cover 40. Being a screw plug, this element also serves as a means for adjusting

the longitudinal position of shaft 35 and may itself be fixed in adjusted position by providing a groove 51a therein, into which extends a rib 58a formed upon a cover plate 58 fixed over said plug and sealing the outer end of opening 41, a suitable gasket 58b being used (see Fig. 4). In order to seal the opening through which extends the drive shaft 51, a dished spring plate 60 is arranged within cover 50 with its margin between the spacer ring 61 which serves to locate the roller bearing 62 supporting the adjacent end of rotor 25, and a suitable gasket 62' carried by the inner face of cover 50.

This dished plate 60 is provided with a central opening for shaft 51 and around said opening is fixed in sealed relation a ring of bearing material 63, preferably "Bakelite" backed with a thin layer of neoprene 63a, while carried by shaft 51 is a second ring 64, preferably steel, against which ring 63 bears. A suitable oil retaining ring 65 of conventional construction may be placed around the shaft 51 where it emerges from cover 50.

It should be noted that each of the piston rods has mounted in it one of the cams 28 and that, while the two outer ones may be placed over its corresponding square portion of shaft 35, provision must be made for placing the central one in place. Such provision is shown in Fig. 7, which shows this one of the cams 28 to be provided with a triangular insert 28a which may be put in place and secured by screws 28b after the cam has been passed over one of the end square portions of the shaft 35.

These three cams 28, in order to function properly, must be fixed as to their angular relation but must be able to move radially. In order to accomplish this, the two end cams have provided in those faces adjacent the center cam, short grooves 128 while the center cam has projecting from both its faces suitable pins 128a.

Figs. 11 and 12 show the two extreme relative radial positions of the three cams 28, Fig. 11 showing the inner position in which the cams are concentric and Fig. 12 showing them in their extreme outer position.

In the construction of the pump, springs 44 and 45 are selected to correspond to the maximum pressure which it is desired that the pump shall deliver. That is, the strength of springs 44 should be sufficient, when partly balanced by spring 45, to maintain shaft 35 in its uppermost position so long as there is little or no back pressure on the pistons 21, but allow the shaft 35 to move down toward a position concentric with the rotor as the delivery pressure increases, and reaches concentricity when the predetermined maximum pressure has been allowed.

In the operation of the pump, rotation of the rotor 25 causes the rotation of cams 28 at double the rotor speed and therefore the rotation of the cams 37 at the same speed, while the speed of rotation of cam 38 will be determined by the position or change of position of shaft 35. So long as the position of shaft 35 is not being changed, the cam 38 will rotate at a speed determined by the eccentric position of the axis of shaft 35, but if the shaft is moving up or down, the cam 38 rotates at a changing rate to suit the change in eccentricity of the shaft. When the shaft 35 reaches its lowest position, and is therefore concentric with the rotor, cams 37 and 38 are arranged exactly opposite and rotate at the same speed.

When back pressure on the pistons has reached

its maximum, and the shaft 35 thereby moved down to a position where the shaft 35 and cams 28 are concentric with the rotor, the two cams 37 and 38 neutralize each other and the two rotate as a circular unit. In such case, no reciprocation of the pistons can take place. When, however, the back pressure begins to drop below maximum, the shaft 35 immediately begins to assume an eccentric position and the cams 28 likewise begin to assume eccentricity so that the piston reciprocation also resumes.

In changing their relations as above mentioned, all of the several cams move simultaneously with the translatable movement of the shaft 35, so that the eccentricity or lift of the cams 28 is always the same as the eccentricity or lift of the cams at the end of the shaft 35.

This result of this equal lift condition of the two groups of cams is a true straight line reciprocation of the pistons in the cylinders and elimination of all side thrust upon the cylinder walls except that small amount due to friction of the parts.

It is obvious that, as the stroke of the pistons is determined by the position of plunger 43, the springs 44 may be omitted and a suitable hand operated means substituted therefor. For example, a simple manually operable screw or threaded shaft may be installed in either end of housing 42 and operated to adjust the position of the plunger 43.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

I claim:

1. In a rotary reciprocating piston pump, a rotor including a radially arranged cylinder, a piston adapted to be reciprocated therein, eccentric means comprising a shaft and a cam thereon for causing straight line reciprocation, said eccentric means being provided with means for varying the eccentricity of said cam with respect to said shaft, and yieldable means biased to maintain said eccentric means at maximum eccentricity, said yieldable means being adapted, under the influence of pump delivery pressure, to permit decrease in said eccentricity with increase in delivery pressure.

2. In a rotary reciprocating piston pump, a rotor including a plurality of cylinders arranged in pairs with the members of a pair diametrically opposite each other, a unitary piston and connecting member assembly for each pair, and means for reciprocating said piston assemblies when said rotor is driven, said means consisting of a circular cam adapted to coact with each said assembly, a rotatable shaft extending through said cams and fixed against rotation relative thereto, means for normally maintaining said shaft eccentric to said cams, means for shifting said shaft to a position concentric to said cams, and means for rotating said shaft and cams at double the rotor speed.

3. In a rotary reciprocating piston pump, a cylinder carrying rotor, pistons reciprocable in said cylinders, eccentric means for reciprocating said pistons, a shaft for supporting said eccentric means, said shaft rotating with said eccentric means during rotation of said pistons, means for driving said pistons at the same rotational speed

as said rotor and means for changing the relation between said shaft and eccentric means whereby to vary the eccentricity of the latter.

4. In a rotary reciprocating piston pump, a rotor provided with a plurality of radially arranged pairs of cylinders, the members of each pair being diametrically opposite, and the pairs equiangularly spaced, pistons for said cylinders, the pistons for each pair being provided with a connecting bar having a central opening, a circular cam mounted for rotation in each of said openings, a rotatable shaft, means for mounting said cams on said shaft in fixed angular relation to each other, means to allow said cams to change their positions relative to the axis of said shaft while maintaining their angular relation, means for supporting said shaft and varying its position in a predetermined straight-line from concentricity with said rotor to any eccentric position up to and including a predetermined maximum eccentricity.

5. In a rotary reciprocating piston pump, a rotor provided with a plurality of radially arranged pairs of cylinders, the members of each pair being diametrically opposite, and the pairs equiangularly spaced, pistons for said cylinders, the pistons for each pair being provided with a connecting bar having a central opening, a circular cam mounted for rotation in each of said openings, a rotatable shaft, means for mounting said cams on said shaft in fixed angular relation to each other, means to allow said cams to change their positions relative to the axis of said shaft while maintaining their angular relation, means for supporting said shaft and

varying its position in a predetermined straight-line from concentricity with said rotor to any eccentric position up to and including a predetermined maximum eccentricity, said supporting means consisting of a circular cam fixed to each end of said shaft and rotatable within another circular cam of equal lift rotatably mounted concentric with said rotor, and resilient means adapted to urge said shaft toward its position of maximum eccentricity.

6. In a rotary reciprocating piston pump, a rotor provided with a plurality of cylinders arranged in pairs, the members of a pair being diametrically opposite each other and the pairs being equiangularly displaced, pistons in said cylinders, means for reciprocating said pistons in said cylinders, said means including a shaft, an eccentric on said shaft for each pair of cylinders, means for fixing the relative angular position of said eccentrics and means for moving said eccentrics to a different position relative to the axis of said shaft to thereby change their eccentricity.

7. In a rotary piston pump, a rotor, a rotary shaft arranged with its axis parallel to the axis of the rotor, and carrying piston actuating means, a circular cam fixed adjacent each end of said shaft, a second circular cam of equal lift rotatable about each of the first cams and themselves rotatable in races concentric with said rotor, and means movable to vary the relation of the axis of said shaft to the axis of the rotor from concentricity to a position of eccentricity.

TOM H. THOMPSON.
